UNITED STATES PATENT OFFICE.

HADLEY C. CLAPP AND EMANUEL LAWSON, OF BREWER, MAINE.

VALVE FOR OIL-CANS.

SPECIFICATION forming part of Letters Patent No. 635,658, dated October 24, 1899.

Application filed January 18, 1899. Serial No. 702,497. (No model.)

To all whom it may concern:

Be it known that we, HADLEY C. CLAPP and EMANUEL LAWSON, citizens of the United States of America, and residents of Brewer, 5 Penobscot county, Maine, have invented certain new and useful Improvements in Valves for Oil-Cans, of which the following is a specification.

This invention relates to oil-cans, and has 10 for its object to provide an improved valve of simple and cheap construction whereby the oil may be prevented from leaking out from the orifice of the can when said valve is closed and providing a free outflow of oil 15 from the orifice of said can when said valve is opened.

In accordance with this invention the valve may consist of a slightly-tapering tube arranged in the side wall of the oil-can near the 20 upper end thereof, and said tapering tube is provided with apertures through the side walls thereof communicating with a nozzle or discharge-pipe and with the interior of the oil-can. A tapering plug is arranged to work 25 within said tube, having an aperture adapted to register with said apertures in said tube when the oil in said oil-can may be poured therefrom through said discharge-pipe, and means is provided to move said aperture in 30 said tapering plug out of register with said apertures in said tube to close said valve. An air-hole is provided and arranged to admit air to said oil-can through said valve as the oil passes out and to close as said valve 35 is closed.

Figure 1 is a side elevation of an oil-can, showing the valve arranged in the side wall thereof open. Fig. 2 is a front elevation of an oil-can, showing the valve closed. Fig. 3 40 is a side elevation of the upper end of an oil-can with a part of the side wall thereof removed, showing the valve in section open; and Fig. 4 is a similar view to that shown in Fig. 3, showing the valve closed.

45 The letter *a* denotes an oil-can of common construction, having a screw-threaded cap *a'*, through which said can may be filled. To prevent the oil from leaking from the orifice or discharge-pipe *d* of said can, a valve is provided consisting of a tube *b*, closed at both ends, which may be made slightly tapering, and said tube *b* is arranged in the side wall

of said oil-can *a* near the upper end thereof. Said tube *b* may be soldered or otherwise secured in the side wall of said oil-can *a*, communicating with the interior thereof, as shown in Figs. 3 and 4. Apertures *c c'* are formed in the side wall of said tube *b*, one of said apertures, *c'*, communicating with the interior of said oil-can *a* and the other opening into said discharge-pipe or nozzle *d*. A tapering plug *e* is provided and adapted to closely fit and work within the interior of said tapering tube *b*, having an aperture *e'* adapted to register with said apertures *c c'*, formed in said tube *b*, when the oil in said oil-can may be discharged through said nozzle *d*. Said tapering plug *e* is constructed and arranged to turn or revolve a part of a revolution to move said aperture *e'*, formed therein out of 70 register with said apertures *c c'*, formed through the side walls of said tube *b*, to close said valve, and said tube *b* has formed therein a radial slot *n*, through which a stud *n'*, secured to said tapering plug *e*, projects, having a thumb-piece *n''* for opening and closing 75 said valve, as shown in Figs. 1 and 2.

Said valve is provided with an air-hole *m*, constructed and arranged to admit air to said oil-can *a* as the oil passes out, said air-hole 80 *m* being formed by piercing said tube *b* and valve-plug *e* with a small hole *m*, as shown in Fig. 3, said hole through said valve-plug *e* moving out of register with said hole *m* through said tube *b* and closing said hole *m* 85 when said valve is closed, as shown in Fig. 4.

We do not wish to limit this invention to a tapering plug *e*, adapted to be turned or revolved radially to open or close the valve, as it is obvious from the construction herein 90 disclosed that said valve may be operated by raising or lowering said valve-plug *e* to move said aperture *e'*, formed therein out of register with said apertures *c c'*, formed in said tube *b*, and in such case said tube *b* and said 95 valve-plug *e*, adapted to work therein, will not be tapered, but will be of uniform diameter.

We claim—

In an oil vessel, a tube or valve-casing set 100 into an elongated opening in the wall thereof so as to project beyond the outer and inner surface of said wall and provided at its lower end with an outlet-opening for the escape of

the contents of the vessel, and at its upper end with an air-inlet opening and a slot, and a valve located in said casing provided at its lower end with an aperture, and at its upper 5 end with an aperture and a pin, the apertures in the valve adapted to simultaneously register with the openings in the valve-casing, and the pin on the valve adapted to project through the slot in the valve-casing and pro-

vide means for operating the valve, substantially as described.

Signed by us, at Bangor, Maine, this 14th day of January, 1899.

HADLEY C. CLAPP.
EMANUEL LAWSON.
